APPARATUS FOR COATING SHAPED
CAN ENDSAlfred L. Kronquest, Syracuse, N. Y., assignor to
Continental Can Company, Inc., New York,
N. Y., a corporation of New York

Application August 6, 1934, Serial No. 738,749

7 Claims. (Cl. 91—42)

The invention relates to new and useful improvements in an apparatus for applying a protective enamel to a can end which has been shaped ready for attachment to the can body. 5 In my prior Patent No. 2,046,197, granted June 30, 1936, there is disclosed a method of applying a protective enamel to a can end which includes the dipping of the face of the can end which is to be coated in a bath of enamel, and then rotating the end rapidly after it is removed from the bath for distributing the coating uniformly over the surface of the end and discharging the surplus enamel from the end by centrifugal force. 10 The can end which is coated by the method of my prior patent is of the commercial form for closing an open top can. The present invention has to do with an apparatus for coating a can end which is cone-shaped and terminates in a neck which may be closed by an ordinary crown seal. Considerable difficulty has been experienced in applying a uniform coating of enamel throughout the entire extent of such a shaped can end, as the neck portion is so shaped as to form pockets which trap the enamel and prevent 15 an even distribution of the coating through the action of centrifugal force thereon.

An object of the present invention is to provide an apparatus which is equipped with means for projecting a stream of air against the freshly 30 coated surface during the rotating thereof and in the regions where the coating is likely to be trapped so as to force the coating from the trap and to cause the coating to be evenly distributed throughout the entire inner surface of the end.

35 A further object of the invention is to provide an apparatus of the above type wherein the air blast is automatically controlled by the shifting of the end to a position free from the bath for the rotating of the same.

40 A still further object of the invention is to provide means for preventing the rotation of the chuck when disconnected from its rotating means and during the connecting of the end to the chuck and the disconnecting of the end therefrom.

45 These and other objects will in part be obvious and will in part be hereinafter more fully disclosed.

50 In the drawings—

Figure 1 is a view partly in side elevation and partly in section showing an apparatus embodying the improvements;

Fig. 2 is an enlarged view showing the can end 55 with the coating applied thereto and positioned for rotation for distributing the coating evenly over the inner surface of the can end;

Fig. 3 is a detail view showing a portion of the neck of the can end with the coating trapped in 60 the pocket formed by the bead at the mouth of

the neck of the can end and prior to subjecting the same to the air blast, and

Fig. 4 is a similar view showing the thinning of the coating by the air blast as the end is rotated.

The invention as above noted is particularly 5 adapted for the coating of a can end which is cone-shaped and drawn so as to provide an integral neck beaded at its open end for the attachment of a crown seal closure or some other similar closure. The can end as shown in the drawings includes a cone-shaped portion 1, a channel portion 2 which is of the usual construction for forming a double seam with the can body, and a neck portion 3. The neck portion 3 is provided with a bead 4 at its upper end which extends 10 from an opening 5 to the shoulder 6. This is for the purpose of providing the shoulder underneath which the projections on the crown seal closure engage for the sealing of the container. It is desired to provide the surface of this end with a 15 protective enamel. It will be impracticable to coat the metal in the sheet before the end is formed, as the strain incident to the drawing of the metal for forming the shape of the end just referred to is likely to break the enamel at points 20 so that certain products placed in the container which would not attack the enamel will re-act upon the exposed metal either to damage the metal, causing pinholing thereof, or to injure the 25 contents of the can, as for example, if the can is used for the packaging of beer. It is well known that if beer contacts with metal it becomes 30 clouded, and therefore, the surface of the metal must be completely covered by the enamel. Applicant's problem resided in the applying of a 35 protective enamel to the entire inner surface of the can end when shaped as described above. The problem was solved by the applying of the 40 enamel coating to the can end preferably by dipping the same in a bath of enamel, and then 45 rotating the end rapidly for the purpose of distributing the enamel in a thin layer over the surface of the end and the discharging of the surplus enamel from the end by centrifugal force. There were still pockets in the region of the neck 50 which trapped the enamel and prevented centrifugal force acting thereon from causing it to flow, leaving a thick coating. This was overcome by the application of a gentle blast of air in the 55 region where the enamel is trapped so as to force it from the trap and permit the centrifugal force to carry it away.

The apparatus consists of a supporting frame 7 which is provided with a tank 8 in which is maintained a bath of coating enamel, the surface of which is indicated at 9. The frame is provided with an arm 10 which overhangs the bath. Mounted in this frame is a sleeve 11 which is formed with a rack 12 at one side thereof. A gear 13 meshes with this rack. The gear 13 60

is carried by a shaft 14 mounted in suitable bearings in the frame and attached to the shaft is a handle 15. By rotating the shaft through the aid of the handle, the sleeve 11 may be raised and lowered in the supporting frame. Extending through the sleeve is a shaft 16 which is hollow. Said shaft is mounted for rotation in bushings 11, 17 carried by the sleeve 11. Fixed to the upper end of this hollow shaft 16 is a cone friction gear 18. Said cone friction gear 18, when the sleeve 11 is raised, is brought into contact with the cone friction gear 19 mounted on the outer end of a shaft 20 of a motor M which is mounted on the supporting frame 7. The motor rotates continuously, and when the sleeve 11 is raised so as to bring the friction gear 18 into contact with the friction gear 19, then the shaft 16 will be rotated, and rotated very rapidly. The motor is preferably of a type that will impart a speed of between three and four thousand revolutions per minute to the shaft 16. Fixed to the lower end of the shaft 16 is a chuck 21. Said chuck 21 is provided with a series of spring arms 22, 22. These spring arms are bent outwardly and curved at 23 so as to conform to the outer surface of the bead 4 at the neck of the can end. The lower ends of these spring arms are bent outwardly as indicated at 24. The can end is placed against these outwardly tapered extending ends 24 and forced into the curved portions which conform to the bead 4 and will be firmly gripped by these spring arms and thus held attached to the chuck. After the end is attached to the chuck, then the lever 15 is turned in a counter-clockwise direction so as to lower the shaft and completely immerse the can end in the bath of enamel. After the end has been completely immersed, it is lifted from the bath with a coating of enamel adhering to the inner and outer surfaces thereof. As soon as the friction gear 18 contacts with the friction gear 19, then the shaft will be rotated rapidly, and this will rotate the end very rapidly. Centrifugal force acting on the coating will cause the coating to flow toward the extreme periphery of the can end. There will be left, however, a thin film of adhering coating over the entire surface of the end, both on the inner and outer faces thereof. The surplus coating will be discharged from the periphery of the end.

During the rotation of the end, the recess formed on the inner face of the bead 4 serves to trap the enamel so that the centrifugal force cannot alone move the enamel from the recess. This is due to the fact that portions of the inner surface of this beaded portion are necessarily of greater diameter than portions of the neck therebelow.

Extending down through the shaft 16 is a pipe 25. Said pipe 25 is provided with a distributing head 26 on the lower end thereof, and said distributing head is formed with a series of openings 27. This pipe 25 is connected to a valve housing 28 which is attached to a pipe line 29 leading to a suitable source of air supply. The pipe 25 is so disposed that when the sleeve 16 is raised to bring the friction gears into contact, that the head 26 is moved down through the opening in the end so that air blasts coming from the openings 27 will contact with the enamel in the trap formed by this inner curved surface at the beaded neck. The air blast is gentle so as not to strip the enamel completely from this surface, but it will cause the enamel to flow from the recess or trap to a point where

it will be taken up by centrifugal force and carried along by the flowing enamel so that it will be distributed and the surplus discharged. The blast of air may be so regulated that the coating of enamel throughout the entire inner surface of the end will be substantially of uniform thickness, and the entire metal surface completely covered by the enamel. 5

In order to regulate the flow of air from the nozzle, there is an arm 30 attached to the shaft 10 14, which arm is connected by a link 31 to an arm 32 connected to a valve in the valve casing 28. When the shaft is lowered for the purpose of applying the coating to the end, the valve is closed, and when the shaft is raised to the position shown in Figures 1 and 2, then the valve is opened so that air flows through the pipe and is discharged against the surface of the end. The blast of air will be released at the same time when the end begins its rotation, and will 20 continue while the end is being rotated.

The arm 10 is provided with a bracket 33 in which is mounted a brake member 34. Said brake member has a reduced shank 35 surrounding which is a spring 36. The spring bears 25 against the head of the brake member, and also against an abutment 37. The purpose of the spring is to hold the brake member projecting from the bracket as indicated in Fig. 1. Said brake member is provided with a tapered face 38 at its upper side and the tapered face 39 at its lower side. This brake member is so positioned that when the shaft is lowered from the position shown in Fig. 1, sufficiently to disconnect the gear 18 from the gear 19, the gear 18 will 35 contact with the brake member and stop its rotation. This is the proper positioning of the shaft for the attaching of the end to the chuck. While said gear 18 is resting against the brake member, the end is placed on the chuck, and then the shaft is lowered, and as it is lowered it is forced by the brake member. On the upward movement of the shaft, the gear will pass the brake member and be freed therefrom so that it may be rotated. 45

From the above it will be apparent that an apparatus has been provided in which a can end may be chucked for rotation, after which the end may be lowered and immersed in a bath of enamel. The end may then be raised and connected to a rotating means whereby it will be rapidly rotated. At the same time, the inner surface of the end throughout any regions which may pocket the enamel are subjected to a gentle blast of air for the purpose of dislodging the 55 enamel from the trap so that the centrifugal force, together with the air blast, will bring about an even distribution of the enamel throughout the entire surface of the can end, thus producing a very thin film completely covering the surface of the metal. After the end is coated, it is dried and may be baked in order to set or harden the enamel. 60

The method employed in the coating of the can end by the apparatus described above forms 65 no part of the present invention, but is shown, described and claimed in my co-pending application Serial No. 5,657, filed February 8, 1935.

Any desired enamel may be used which may be flowed over the surface of the end. Instead 70 of immersing the end in order to provide the initial supply of enamel, it may be applied to the end by spraying, but preferably the end is dipped as this produces a surplus of enamel which can be spread over the surface of the end 75

and the surplus discharged, leaving a more uniform coating, and insuring that the entire surface of the metal will be coated, particularly in the inner face thereof, so that no product within the container can contact with the metal of the end.

Having thus described the invention, what I claim as new and desire to secure by Letters Patent, is—

10 1. An apparatus for applying a protective enamel to the inner face of a formed can end comprising a supporting frame, a tank carried thereby having a bath of enamel therein, a projecting arm overhanging said bath, a chuck to which the end may be attached, a support for said chuck, means for moving said support vertically for immersing the end in the bath, means for rotating said support, and means for directing a blast of air against the coated surface, where desired, during the rotation thereof for aiding in the forming of a coating of uniform thickness.

25 2. An apparatus for applying a protective enamel to the inner face of a formed can end comprising a supporting frame, a tank carried thereby having a bath of enamel therein, a projecting arm overhanging said bath, a chuck to which the end may be attached, a support for said chuck, means for moving said support vertically for immersing the end in the bath, means for rotating said support including friction gears contacting with each other only when said chuck is raised to its extreme elevated position, and a yielding brake adapted to prevent the rotation of said support when the gears are out of contact and while the ends are being attached to and removed from the chuck and while the end is being immersed in the enamel bath.

30 3. An apparatus for applying a protective enamel to the inner face of a formed can end comprising a supporting frame, a tank carried thereby having a bath of enamel therein, a projecting arm overhanging said bath, a chuck to which the end may be attached, a support for said chuck, means for moving said support vertically for immersing the end in the bath, means for rotating said support including friction gears contacting with each other only when said chuck is raised to its extreme elevated position, and 35 means for directing a blast of air against the coated surface, where desired, during the rotation thereof for aiding in the forming of a coating of uniform thickness.

40 4. An apparatus for applying a protective enamel to the inner face of a formed can end comprising a supporting frame, a tank carried thereby having a bath of enamel therein, a projecting arm overhanging said bath, a chuck to which the end may be attached, a hollow shaft to which 45 said chuck is attached, a sleeve in which said shaft is mounted for rotation, means for raising and lowering the sleeve for causing the can end carried by the chuck to be immersed in the bath and removed therefrom, a friction gear attached 50 to said shaft, a motor-driven friction gear carried by the frame and positioned so that when 55 said sleeve is in elevated position, said gears will contact and the shaft will be rotated, and a pipe extending through said hollow shaft and having 60 a head at the lower end thereof provided with 65 openings through which air jets may be directed

against the inner surface of the can end at the regions desired and during the rotation thereof.

5 5. An apparatus for applying a protective enamel to the inner face of a formed can end comprising a supporting frame, a tank carried thereby having a bath of enamel therein, a projecting arm overhanging said bath, a chuck to which the end may be attached, a hollow shaft to which said chuck is attached, a sleeve in which 10 said shaft is mounted for rotation, means for raising and lowering the sleeve for causing the can end carried by the chuck to be immersed in the bath and removed therefrom, a friction gear attached to said shaft, a motor-driven friction gear carried by the frame and positioned so that when 15 said sleeve is in elevated position, said gears will contact and the shaft will be rotated, a pipe extending through said hollow shaft and having a head at the lower end thereof provided with openings through which air jets may be directed 20 against the inner surface of the can end at the regions desired and during the rotation thereof, a valve in said air pipe, and devices controlled by the movement of the sleeve so that said valve is opened for discharging air against the surface 25 of the can end only during the time when said end is to be rotated.

6. An apparatus for applying a protective enamel to the inner face of a formed can end comprising a supporting frame, a tank carried thereby having a bath of enamel therein, a projecting arm overhanging said bath, a chuck to which the end may be attached, a hollow shaft to which said chuck is secured, a sleeve on which 30 said shaft is mounted for rotation, said sleeve having a rack on one side thereof, a pinion engaging said rack, a shaft carrying the pinion, means for rotating said pinion shaft for raising and lowering the sleeve, a friction gear carried at the upper end of said hollow shaft, a motor-driven 35 friction gear mounted on the frame and adapted to contact with the gear on the hollow shaft when the sleeve is elevated for the rotating of the chuck and the container end carried thereby.

7. An apparatus for applying a protective 40 enamel to the inner face of a formed can end comprising a supporting frame, a tank carried thereby having a bath of enamel therein, a projecting arm overhanging said bath, a chuck to which the end may be attached, a hollow shaft to 45 which said chuck is secured, a sleeve on which said shaft is mounted for rotation, said sleeve having a rack on one side thereof, a pinion engaging said rack, a shaft carrying the pinion, means for rotating said pinion shaft for raising and lowering the sleeve, a friction gear carried at the upper end of said hollow shaft, a motor-driven 50 friction gear mounted on the frame and adapted to contact with the gear on the hollow shaft when the sleeve is elevated for the rotating of the chuck and the container end carried thereby, and a pipe extending through said hollow shaft and having a head at the lower end provided with openings through which jets of air 55 may issue, said pipe being disposed so that when the sleeve is raised and the gears connected for rotation, the head of said pipe will extend through the opening in the can end and cause the air jets to engage the inner surface of the can end.
